CLAIM

The ornamental design for a toggle switch, substantially as shown and described.

DESCRIPTION

FIG. 1 is a front elevational view of a toggle switch showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is an enlarged cross-sectional view of the switch taken along line 7—7 of FIG. 3;

FIG. 8 is a perspective view thereof.

FIG. 1

FIG. 2

FIG. 3

FIG. 4

FIG. 5

FIG. 6

FIG. 7

FIG. 8
